United States Patent Office

Des. 187,975
Patented May 24, 1960

187,975

PETTICOAT OR THE LIKE

Gladys Williams, New York, N.Y., assignor to Schiller Bros., Inc., New York, N.Y., a corporation of New York

Filed Jan. 13, 1958, Ser. No. 49,236

Term of patent 14 years

(Cl. D3—26)

FIG. 1

FIG. 2

FIG. 3

FIG. 4

Fig. 1 is a front elevation of a petticoat or the like showing my new design;

Fig. 2 is a rear elevation of the same;

Fig. 3 is a side elevation of the same; and

Fig. 4 is a rear elevational view of the same with the back panel lifted and a flap turned back.

I claim:

The ornamental design for a petticoat or the like, as shown.
